PLATE STEEL CASING JOINT FOR ROTARY HYDRAULIC MACHINES

Filed April 26, 1944

improved arrangement of overlapping casing and stay ring elements whereby the casing plates may be curved very closely to the stay vanes 8 thereby to permit desirable velocity and flow conditions to be obtained while at the same time insuring maximum structural strength to the joints between the casing and stay vane ring. It is, of course, to be understood that the keyed straps will be formed in segmental lengths.

It will of course be understood that various changes in details of construction and arrangement of parts may be made by those skilled in the art without departing from the spirit of the invention as set forth in the appended claims.

I claim:

1. A rotary hydraulic apparatus comprising, in combination, a stay vane ring and a volute plate steel casing therefor having certain small sections that are relatively small compared to others, said stay vane ring having a portion 20

overlapping one side of said plate steel casing near its edge portion, a rivet strap overlying the other side of the plate steel casing, and means for anchoring said strap to the stay vane ring by a direct abutting contact with a transverse surface on said ring whereby rivets extending through said strap, plate and ring will be placed in double shear to provide necessary strength and to allow curvature of the casing at its small sections to start adjacent the stay ring thereby to obtain more desirable flow conditions through the volute casing.

2. The combination set forth in claim 1 further characterized in that a head cover is provided with a recess to receive said stay vane ring, and said ring has an annular ledge at its innermost edge and the strap has a flanged portion seated in said recess and overlapping and engaging said edge.
